UNITED STATES PATENT OFFICE.

JOSEPH E. MANLOVE, OF PLYMOUTH, ILLINOIS.

SPARK-PLUG.

1,223,188.

Specification of Letters Patent. Patented Apr. 17, 1917.

Application filed July 21, 1916. Serial No. 110,558.

To all whom it may concern:

Be it known that I, JOSEPH E. MANLOVE, a citizen of the United States, residing at Plymouth, in the county of Hancock and

5 State of Illinois, have invented certain new and useful Improvements in Spark-Plugs; and I do hereby declare the following to be a full, clear, and exact description of the invention, such as will enable others skilled 10 in the art to which it appertains to make and use the same.

This invention relates to improvements in spark plugs, and has for its primary object to provide a device of this character em-

15 bodying a hollow body having connection with the fuel inlet pipe or manifold of an internal combustion engine, whereby the explosive mixture is drawn through the hollow body and into the explosion chamber

20 of the cylinder during the suction stroke of the piston to prevent the accumulation of dead gas within the plug and also to insure against the accumulation of carbon and other deposits upon the electrodes of the

25 spark plug.

Another object is the provision of a novel type of electrode carrying a substantially cup shaped member.

With these and other objects in view, the 30 invention consists in the novel construction, combination and arrangement of parts as will be hereinafter specifically described, claimed and illustrated in the accompanying drawing, in which:

35 Figure 1 represents a fragmentary sectional view through the head of the cylinder of an explosive engine, showing the improved spark plug in side elevation,

Fig. 2 represents a longitudinal sectional 40 view through the improved spark plug, and

Fig. 3 represents a fragmentary sectional view through the insulator and center electrode.

Referring to the drawing in detail, where- 45 in similar reference numerals designate cor- responding parts throughout the several views, the numeral 5 indicates the body of the improved spark plug, which is of hol- low formation and is formed integral with 50 a reduced and externally screwthreaded ex- tension 6 adapted to be secured in the usual spark plug receiving opening 7 formed in the wall or head of the cylinder 8 of an ex- plosive engine. The body 5 is formed cen- 55 trally with an external shoulder 9 forming a stop for a circumferential enlargement 10

formed upon the insulator 11, which latter is positioned through the body and exten- 60 sion 6 and is secured in position by a ring nut 12.

The center electrode 13 is rigidly secured in the insulator 10 and the end thereof which terminates adjacent the open end of the hollow extension 6 is connected with a substantially cup shaped member 14, which 65 latter is constructed of the same material as the electrode 13 and is disposed in spaced relation to the other or outer electrode 15, which is carried by the end of the exten- 70 sion 6.

The bore of the body 5 is enlarged intermediate its ends, as indicated at 16, and the wall of the enlarged portion is formed with a plurality of radial inlet ports 17. As clearly shown in Fig. 2 the insulator 10 is 75 disposed in spaced relation to the portion of the wall of the bore of the body intermediate the shoulder 9 and the hollow extension 6, so as to permit the explosive mix- 80 ture admitted to one of the openings 17 to flow into the explosion chamber of the engine. Several of the inlets 17 of the body are closed by removable screws or plugs 18 and another of the inlet ports is closed by a plate 19, which is attachable to any one of 85 the several side faces of the body 5 and is formed with a transverse opening 20, com- 90 municating with the inlet port 17. The opening 20 through the plate 19 is reduced in diameter intermediate its ends to present 95 a seat 21 for an outwardly closing check valve 22, which is normally retained in closed position by a spring 23 and is de- 100 signed to prevent the fire from the explosion occurring in the explosion chamber of the engine from entering the fuel pipe or mani- 105 fold 20, which latter is attached to the block or plate 19.

In use, the spark plug is secured in the 100 opening 7 in the wall of the cylinder 8 in the usual manner and during the operation of the engine the electric spark jumps between the electrode 15 and the cup shaped member 14. The explosive mixture is con- 105 ducted from the fuel pipe 24 through the port 17 and hollow body 5 and extension 6 to the explosion chamber and the intermit- 110 tent flow of the mixture over the electrodes 13 and 14 and the coupling member 14 pre- vent premature fouling of the electrodes. In starting the explosive engine the heavy vapor or mixture passing through the hol-

low body in the spark plug contains small particles of liquid fuel, which is deposited in the cup shaped member 14 where it will be readily ignited by the spark which jumps 5 between the cup shaped member 14 and the electrode 15.

What I claim is:

A spark plug comprising a hollow rectangular body, a hollow externally screw-threaded extension formed on said body for threaded engagement with the head of an engine, a shoulder formed on the interior of the body and centrally thereof, an insulator having a circumferential enlargement extending through the body and into the extension and having the enlargement disposed against the shoulder, said body hav-

ing oppositely disposed inlet ports communicating with the interior thereof at a point below the shoulder, a plate closing one of 20 said inlet ports and having a transverse opening provided with its walls beveled to form a valve seat, plugs closing the other inlet ports, a spring pressed valve normally closing the transverse opening of the plate, 25 a fuel supply pipe connected to the transverse opening, and electrodes carried by the insulator and extension.

In testimony whereof I affix my signature in presence of two witnesses.

JOSEPH E. MANLOVE.
